US00D912068S

(12) **United States Design Patent** (10) **Patent No.:** **US D912,068 S**
(45) **Date of Patent:** **** Mar. 2, 2021**

(54) **DISPLAY SCREEN WITH GRAPHICAL USER INTERFACE**

CPC G06F 17/211; G06F 17/212; G06F 3/1251;
G06F 3/0481; G06F 2203/04807; G06T
2200/24

See application file for complete search history.

(71) Applicants: **Diana Maureen Wiffen**, Waterloo (CA); **Jad John Saliba**, Waterloo (CA); **Geoffrey Wendell MacGillivray**, Waterloo (CA); **Michael Charles Parkhill**, Waterloo (CA); **Samantha Jo McIlveen**, Waterloo (CA); **Tayfun Uzun**, Waterloo (CA); **Jamie Robert Earl McQuaid**, Waterloo (CA); **Paul Stephen Hendry**, Waterloo (CA)

(72) Inventors: **Diana Maureen Wiffen**, Waterloo (CA); **Jad John Saliba**, Waterloo (CA); **Geoffrey Wendell MacGillivray**, Waterloo (CA); **Michael Charles Parkhill**, Waterloo (CA); **Samantha Jo McIlveen**, Waterloo (CA); **Tayfun Uzun**, Waterloo (CA); **Jamie Robert Earl McQuaid**, Waterloo (CA); **Paul Stephen Hendry**, Waterloo (CA)

(73) Assignee: **MAGNET FORENSICS INVESTCO INC.**, Waterloo (CA)

(**) Term: **15 Years**

(21) Appl. No.: **29/657,491**

(22) Filed: **Jul. 23, 2018**

Related U.S. Application Data

(63) Continuation of application No. 29/557,752, filed on Mar. 11, 2016, now Pat. No. Des. 823,860.
